UNITED STATES PATENT OFFICE.

LESLIE B. GRAHAM, OF EAST CHICAGO, INDIANA, ASSIGNOR TO UNION METAL PRODUCTS COMPANY, OF CHICAGO, ILLINOIS, A CORPORATION OF DELAWARE.

CAR-COUPLER POSITIONING DEVICE.

Application filed July 6, 1926. Serial No. 120,674.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range."

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the

number of broken knuckles and guard arms on couplers which members are frequently bent or broken when the couplers are not within coupling range. Such devices also reduce the number of accidents to trainmen as they are not required to go between the cars and position the coupler preparatory to coupling.

A common form of car coupler positioning device comprises a coupler carrier swingably suspended by links from some part of the car so that the objects and advantages mentioned above are obtained and my invention in an improvement upon such devices and consist in providing a double trunnion construction to increase the eccentricity of the weight of the coupler (and its associated parts) about the point of support, thus increasing the resultant force tending to return the coupler to the longitudinal center of the car (or away therefrom when the car is tipped).

In my device the coupler carrier is swingably suspended from any convenient part of the car by a link at each of its ends. At least one of these links has spaced apart trunnions both preferably supporting the coupler carrier when it is in its normal central position. When the carrier swings in one direction, one of the trunnions moves away from its journal bearing, thus shifting the load on the link entirely to the other portion. A similar action takes place when the carrier swings in the opposite direction. It is preferable that the carrier maintain a horizontal position at all times, which is accomplished by arranging the links so that a vertical plane passing through the pivot connection of the link, bisects the distance between the spaced apart trunnions of the link, or when the double trunnion construction is used at both ends of a link, a vertical plane bisects the distances between the pairs of spaced apart trunnions. The double trunnion construction may be used on one or both ends of one or both links.

In the drawings:

Fig. 1 shows a typical application of my device to a railway car.

Fig. 2 is a side elevation of Fig. 1.

Fig. 3 is a skeleton diagram with the carrier moved laterally.

Fig. 4 is a detail of the link.

Figs. 5 and 6 are skeleton diagrams showing a modified form of the device, respectively,

when the carrier is in normal position and with the carrier moved laterally.

In the form shown in Figs. 1 to 4, inclusive, the upper ends of the links 2 are provided with two spaced apart pintles or trunnions 3—4 which engage pairs of spaced apart journal bearings 5—6 on opposite sides of an aperture 7 (or slot) in the car part 8 preferably when the coupler 9 and carrier 10 are in normal central position. Some means, such as lugs 11, are provided to prevent lateral movement of the coupler relative to the carrier, thus stabilizing the device. A wall 12 is interposed between the journal bearings 13 to prevent the trunnions from slipping sideways so as to maintain them in operative position. The links are pivotally connected to the carrier (13) in any desired manner. When the coupler moves laterally toward the right (for instance) the entire load on the link 2 is shifted to the left trunnion 3, as shown in Fig. 3. In this position the eccentricity of the load about its support is the horizontal distance "B" between vertical planes 14 and 15 passing, respectively, through the supporting point of the trunnion of the link and the pivot point (13) between the link and the carrier 10.

This double trunnion construction may be used on one or both of the links or may be used on one or both ends of one or both links. The actual adaptation of the invention will depend upon the amount of power desired to operate the device and clearances to be met by the designer.

In the form shown in Figs. 5 and 6 the links 30 are provided with a double pintle or trunnion construction at each end. These double trunnions engage pairs of spaced apart journal bearings on opposite sides of apertures (or slots) in the car part and carrier, respectively, when the device is in normal position. A wall is interposed between the pairs of journal bearings on the car part (12) and carrier (31), respectively, to prevent the trunnions from slipping and so as to maintain them in operative position. When the carrier 32 moves laterally toward the right (for instance) the entire load on the link is shifted to the left upper trunnion 3 and simultaneously the entire load of the carrier 32 is shifted to the right lower trunnion 33 of the link. In this position the eccentricity of the load about its support is the horizontal distance "C" between vertical planes, one of which 34, passes through the center of the left upper trunnion and the other of which 35 passes through the center of the right lower trunnion of the link. It is desirable to maintain the carrier (10 or 32) in a horizontal position at all times so as not to twist or torsion on the coupler, therefore, when the coupler moves laterally, both ends of the carrier must rise an equal amount. When the double trunnion construction is

used at one end of the link, this parallelogram action is obtained by positioning the link 2 so that a vertical plane 36 passing through the pivoted connection 13 bisects the distance between the trunnions 3 and 4. When the double trunnion construction is used at one end of the link the parallelogram action is obtained by positioning the link 2 so that a vertical plane 36 passing through the pivoted connection 13 bisects the distance between the trunnions 3 and 4. When the double trunnion construction is used at both ends of a link 30, a vertical plane 37 bisects the distances between the oppositely disposed pairs of trunnions (3—4) and (33—40).

Fig. 4 shows the link 2 of the form illustrated in Figs. 1 to 3, inclusive. The link comprises a shank 41 with spaced apart trunnions 3—4 forming journals at one end and a single trunnion 42 at the other end. If a pin is used to pivotally connect the link at one end, that end could be perforated for the pin.

The links are preferably duplicates to simplify manufacture, application and accounting. They are symmetrical with respect to a vertical center plane across their lengths and if the double trunnion construction is used at both ends of a link, it may be symmetrical with respect to center planes across its width and length.

The drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car, the combination of a car part having two pairs of parallel spaced apart journal bearings, a coupler carrier swingingly suspended from said car part by a pair of links, said links having spaced apart parallel trunnions at their upper ends engaging said journal bearings when the device is in normal position, one trunnion of each link moving out of engagement with its bearing when the carrier moves laterally.

2. In a railway car; the combination of a car part element, a coupler carrier element swingably suspended therefrom by a pair of links, each of said elements having two parallel spaced apart journal bearings, one of said links having spaced apart parallel trunnions at both ends engaging said journal bearings of said elements, respectively, when the device is in normal position, two of said trunnions moving out of engagement with its journal when the carrier moves laterally.

3. In a railway car, the combination of a car part having two pairs of parallel spaced apart journal bearings with a wall therebetween, a coupler carrier swingingly suspended from said car part by a pair of links, said links having spaced apart parallel trunnions

at their upper ends engaging said journal bearings when the device is in normal position, one trunnion of each link moving out of engagement with its bearing when the carrier 5 moves laterally.

4. In a railway car; the combination of a car part element, a coupler carrier element swingably suspended therefrom by a pair of links, each of said elements having two par-

10 allel spaced apart journal bearings, one of said links having spaced apart parallel trunnions at both ends engaging said journal bearings of said elements respectively, when the device is in normal position, two of said

15 trunnions moving out of engagement with its journal when the carrier moves laterally, the parts so positioned that a vertical plane bisects the distances between the oppositely disposed pairs of trunnions.

20 5. An article of manufacture, a car coupler carrier having each end bifurcated to form spaced apart portions, each of said portions having two parallel journal bearings with a wall therebetween.

25 6. An article of manufacture; a suspension link for car coupler carriers having spaced apart parallel trunnions at each end.

7. An article of manufacture; a suspension link for car coupler carriers having spaced 30 apart parallel trunnions at each end, said link

being symmetrical with respect to center planes across its width and length.

8. An article of manufacture; a suspension link for car coupler carriers having spaced apart parallel trunnions at one end. 35

9. In a railway car, the combination of a car part having a slot with a pair of spaced apart bearings on each side thereof, a coupler carrier having each end bifurcated to form spaced apart portions, each of said portions having a pair of spaced apart bearings, and a pair of links swingably suspending said carrier from said car part, each of said links having a pair of spaced apart trunnions at each end, each trunnion at the upper ends engaging bearings on opposite sides of the slot, each trunnion at the lower ends engaging bearings on the opposite bifurcated portion. 40 45

10. In a railway car; the construction of a car part element, a coupler carrier element, with one of said elements having parallel spaced apart journal bearings and a pair of links swingably suspending said carrier from said car part, one of said links having spaced apart parallel trunnions engageable with said 50 journal bearings, whereby the load supported by the link is shifted to one bearing at a predetermined position of the carrier during its swinging movement. 55
